UNITED STATES PATENT OFFICE

GEORGE B. SMALL, OF TULSA, OKLAHOMA, ASSIGNOR OF THREE-FOURTHS TO TIDAL OIL COMPANY, OF TULSA, OKLAHOMA, A CORPORATION OF OKLAHOMA

PNEUMATIC PUMPING APPARATUS

Application filed November 15, 1929. Serial No. 407,397.

My invention relates to pneumatic pumping apparatus, and more particularly to apparatus of that character for automatically evacuating oil wells of limited production at intervals determined by rapidity of accumulation of fluid in the wells, the present invention constituting an improvement on the apparatus disclosed in Letters Patent of the United States No. 1,724,854 and No. 1,724,858, issued to me under date of August 13, 1929, and having for its principal object the adaptation of such apparatus for use on wells of different depths, capacities and gas pressures; the principal novelty of the present invention consisting of employment of the air or gas pressure, regardless of its degree, and of differential pressures in the discharge line, regardless of degree of the discharge line pressure or of the total volume of discharge for control of supply of gas or air for discharging the well.

In accomplishing these objects, I have provided improved details of structure, the preferred form of which is illustrated in the accompanying drawings, wherein:

Fig. 1 is a perspective view of apparatus embodying my invention, connected with the casing head, the tubing and the discharge line of an oil well.

Fig. 2 is a vertical perspective section of the pumping apparatus and portions of the well, showing the major and minor air flow valves closed.

Fig. 3 is a similar sectional view showing the valves open.

Fig. 4 is a vertical section of the minor flow valve mechanism on the line 4-4, Fig. 5, showing the minor valve closed.

Fig. 5 is a cross section of the minor flow valve mechanism on the line 5-5, Fig. 4.

Fig. 6 is a detail perspective view of the minor valve head.

Fig. 7 is a central longitudinal section of the pressure reducing element in the minor flow supply line.

Referring in detail to the drawings:

1 designates a well hole leading through cap rock 2 to a shot hole 3 in oil sands 4; 5 the well casing supported by a shoe 6 on the cap rock 2; 7 a casing head, and 8 tubing 50 extending through a stuffing box 9 in the casing head and through the casing into the shot hole of the well, all in accordance with ordinary practice.

Suspended from the lower end of the tubing within the shot hole is a trap 10 having a reducing coupling 11 on its lower end carrying a strainer 12, the upper end of which projects into the trap. Mounted on the strainer within the trap is a foot valve 13 having ports 14 opening to the trap, and provided on its upper end with a nipple 15.

Mounted on the foot valve and communicating with the nipple is a pipe 16 which extends up through the tubing 8 to anchorage 65 in a T-fitting 17 on the top of the tubing above the casing head.

Connected with and extending above the T-fitting is a coupling tube 18 carrying a Venturi tube 19 having a receiving chamber 20, a reduced throat 21 70 and an expansion chamber 22. Threaded into the end of the expansion chamber is an offtake line 23, through which fluid discharged from the well may pass to storage or for disposal through a flow line, the pipe 16, coupling 18, tube 19 and line 23 constituting a discharge line for fluid from the trap in the well.

Threaded into one of the connections of the T-fitting 17 is a pipe 24 communicating with the tubing 8 through the annulus in the fitting about the discharge pipe, and mounted on said pipe 24 is a major flow valve housing 25 which will presently be described 80 in detail, the pipe 24 being equipped with an orifice coupling 26 for preventing a sudden rush of air or gas into the well and thereby obviating obstruction of valves in the line by dust or dirt which might be car- 85 90

ried into the line with the initial flow of such pressure medium.

The housing 25 includes a valve chamber 27 having a downwardly facing seat 28 and 5 a throat 29 providing communication between the chamber 27 and a distributing chamber 30, which communicates with the pipe 24 through channel 31 and with a vent chamber 32 through a throat 33; the throat 10 33 having an upwardly facing valve seat 34 at its upper end, and the vent chamber having an outlet line 35 through which air vented from the tubing to chamber 32 may be conducted to a distance from the valve 15 housing.

Extending vertically in the housing 25 coaxially with the throat 33 is a bore 36 opening to a diaphragm chamber 37 formed by flanges 38 and 39 on the upper face of the 20 head 40 and on the under face of a cover member 41 held to the head 40 by bolts 42, a flexible diaphragm 43 extending across the diaphragm chamber and having its edge interposed between the flanges 38 and 39 of the 25 housing head and cover member to anchor the diaphragm securely in place. The diaphragm 43 constitutes a motor for opening the major valve as will presently be disclosed.

Slidable in the bore 36 is a piston 44 having a valve head 45 on its lower end adapted for cooperation with the seat 34 to close the throat 33 and prevent escape of air or gas, hereafter referred to as air, through the throat and to the vent chamber 32, and of 30 such length as to extend into the diaphragm chamber 37 and flex the diaphragm when the piston is in its upper position.

Fixed to the piston 44 is a stem 46 which extends through the throat 33, the distributing 40 chamber 30 and the throat 29 into the chamber 27, where it carries a valve 47 having a face 48 adapted for cooperation with the seat 28 to prevent flow of air from chamber 27 into the distributing chamber 30. 45 Threaded into the chamber 27 is the coupling 49 of a major flow line 50, through which air is supplied under high pressure from a compressor or other suitable source indicated at 51.

50 Mounted adjacent the housing 25, preferably by arms 52 on the cover member of the major valve housing, is a minor flow valve housing made up of several parts but designated generally by the numeral 53, and including a central member 54 containing a chamber 55 counterbored to accommodate the gland of a stuffing box 56.

Attached to the bottom of the central member 54 by bolt and flange coupling 57 is a 60 lower diaphragm unit 58 including a cap 59 attached to the body of the unit by the usual bolt and flange coupling indicated at 60, the body member and cap having flanges 61-62 65 forming a chamber 63 for the diaphragm 64

having its edge clamped between the flanges 61-62 of the body and cap members.

Mounted on the upper end of the central housing member 54 by bolt and flange connection 65 is a diaphragm housing 66 including body and cap members 67-68, and provided respectively with flanges 69-70 forming a chamber 71 for the flexible diaphragm 72 having its edge clamped between the flanges 69-70 of the body and cap members. 75 The lower section of the chamber 71 is extended downwardly to form a guide chamber 73 having a clearance extension 73' for the guide member 74 on the diaphragm 72.

The cap member 68 includes a dome 75 80 housing a chamber 76 having open communication with the upper section of the diaphragm chamber 71.

Located in the chamber 55 of the central housing member 53 is a slide valve 80 having an arcuate end 81 of a curvature corresponding to the wall of the chamber, and provided with a recess 82 adapted for establishing communication between an inlet port 83 and a vent port 84 when in one position; the valve being of such depth as to expose the port 83 to the lower portion of the chamber 55 when the valve is in its elevated position.

The valve member 80 has flat, tapered sides 85-86 providing channels in the chamber 84, through which the port 83 may communicate with an inlet port 87, the valve member having a guide groove 88 in its reduced end, into which a stud 89 on the inner wall of the chamber 54 is projected for retaining the valve member in position for controlling the ports 83 and 84 without interfering with its slide movement.

Fixed to the lower end of the valve member 80 is a stem 90 which extends through a stuffing box 91 on the body member of the lower diaphragm housing 58 and through a bore 92 in said housing into a chamber 93 formed as a counterbore to the recess 63, constituting the upper section of the diaphragm chamber 105 in said housing and carries a head 94 in its lower end fixed to the diaphragm 64 and to the reinforcing strip 95 on said diaphragm.

Slidable in the stuffing box 56 on the body member 67 of the upper diaphragm housing 66 and in a bore 97 in said body member is a stem 98 secured to the head 74 in the lower section 73 of the chamber in said housing, and engageable with the diaphragm 72 therein.

The diaphragms 64 and 72 at the ends of the secondary valve housing constitute motors for opening and closing the secondary valve as will presently be described.

The valve structure represented by the housing 53 and its contained parts is for effecting opening and closing of the major flow line valve to control supply of air to the well under high pressure for discharging the well, and is operated to open the valve by a minor flow of air and to close the valve in response 125 130

to differential velocities of flow of fluid, in the well discharge line, as I will now describe.

Opening from the major flow or high pressure air line 50 is a T-coupling 100. Leading from one branch of the coupling 100 is a line 101 including a pressure reducer 102, preferably consisting of a barrel 103 containing a plurality of spaced orifice plates 104 providing a plurality of expansion chambers and 10 reducing throats for effecting progressive drop in pressure of the air flowing therethrough.

The line 101 carries a T-fitting 105, one branch 106 of which connects through a T-fitting 107 with a line 108 extending through the well casing to a point in the well exterior to the trap 10 and below the level to which oil will rise in the well under its natural pressure so that when the well has filled to its natural level, the lower end of the line 108 will be submerged and liquid sealed.

Also leading from the T-fitting 105 on the line 101 is a line 110 terminating in a port 111 in the cap member 59 of the lower diaphragm housing of the secondary valve mechanism, and communicating with the lower section of the diaphragm chamber 63 in said housing so that air from the high pressure line, after reduction in pressure, will flow 30 to the well and to the diaphragm chamber 63 under the same pressure when the line 108 is unsealed. When the line 108 is sealed by submergence in the well, pressure builds up in the line leading to the diaphragm chamber 35 to a degree equal to that of the submergence head in the well.

Opening from the top of the well is a line 112 leading through a port 113 into the top section of the lower diaphragm chamber 63 40 of the secondary valve mechanism so that, when the line 108 leading to the well is open, absolute pressure in the well is equalized responsive to air supplied to the well through line 108 and to gas originating in the upper 45 and lower sections of the diaphragm chamber.

Leading from the coupling 100 on the high pressure or major flow line to the port 87 of the slide valve chamber 55 is a line 114, through which air under high pressure but 50 in reduced volume may pass from the major flow line to the valve chamber for passage around the slide valve 80 to the outlet port 83 when the latter is opened by elevation of the slide valve, air passing through the line 114 55 being trapped in the chamber 55 when the port 83 is closed.

Connected in the port 83 is a line 115 leading to a port 116 in the cap member 41 of the major valve housing 25, and opening to the 60 upper section of the diaphragm chamber 37 in said housing, so that when the line 115 is open a minor flow of air passes to the chamber in said housing for actuating the diaphragm.

65 With the parts heretofore mentioned con-

structed and assembled as described, the major valve is held closed by pressure of air in the major flow line against the valve 47, and the minor flow of air to the diaphragm motor 43 is shut off by the slide valve 80 which assumes its lowest position when pressure on the diaphragm in the lower housing of the secondary valve mechanism is under balanced pressure due to open communication of the lines 108 and 112 with the well when the line 108 is not submerged.

When the line 108 is submerged, pressure building up in lines 108 and 110 expands the diaphragm 64 to lift the slide valve and open the port 83 so that air from line 114 may pass through the slide valve chamber and line 115 to operate the major valve motor and open the major valve.

As soon as flow to the well is established through the major or high pressure line, 85 equalization of pressure on the slide valve opening diaphragm is reestablished through a vent fitting 117 on the minor flow line 108, including a diaphragm housing 118 containing a chamber 119, the lower section of which 90 is connected with the line 108 through a throat 120 having vent ports 121.

The throat 120 has a downwardly facing valve seat 122 for a ball valve 123 on a stem 124 having a head 125 attached to the diaphragm 126 in chamber 119, the ball valve being yieldingly held to its seat by a spring 127 seated in the fitting 107 connecting the fitting 117 with the line 108, but providing for free flow of air to the vent when the valve is unseated.

The upper section 128 of the diaphragm chamber 119 communicates with the major or high pressure air line 24 through a nipple 129 so that as soon as high pressure air is admitted to the line 24, some of the air is transmitted to the diaphragm chamber to operate the valve 123 and vent the line 108, thereby relieving the line 110 and diaphragm 64 so that the slide valve may be returned to closed position. The slide valve, however, remains in its elevated position to permit continuation of minor flow of air to the major valve motor for retaining the valve open until it returns to shut off the minor flow by actuation of the diaphragm motor in the upper housing section 66, as I will now describe.

Opening from the chamber 20 in the Venturi tube is a line 130 leading through a port 131 in the cap member of the motor housing 66 into the upper section of the diaphragm chamber 71 in said housing, and opening from the Venturi throat 21 is a line 132 leading through the port 133 of said upper diaphragm housing to the lower section of said diaphragm chamber 71, through the valve head chamber 73 and through a branch port 134 so that under normal conditions of low velocities in the Venturi chamber and throat, there will be such low differential of pressure 130

in the upper and lower sections of the diaphragm chamber 71 as not to unbalance the diaphragm, but under certain conditions of discharge of the well, pressure in the upper section of the diaphragm chamber will exceed that in the lower section, and the slide valve will be closed in response to the differential in pressures induced by differential in velocities in the Venturi tube.

Assuming the parts to be constructed and assembled as described, with the valve mechanism connected with the well and pressure in the major flow line, when the well starts to fill the major flow valve is closed by pressure in the major line and the secondary slide valve is in its lowermost position (Figs. 2 and 4), venting the diaphragm chamber in the major valve housing and cutting off supply of air to the major valve chamber.

The minor flow of air through the branch on the high pressure line 50 passes through minor flow line 108 into the well casing above the incoming oil, and also passes through the line 110 to the bottom of the lower section of the bottom diaphragm housing of the secondary valve mechanism; air leaving the well through the line 112 passing to the upper section of said diaphragm housing under the same pressure as the air in the lower section, thereby equalizing pressures on the diaphragm. Pressures in the Venturi chamber 20 and throat 21 being equal under these conditions, pressures in the upper and lower sections in the diaphragm chamber at the top of the secondary valve mechanism are also equalized through the lines 130 and 132. Consequently, the slide valve remains in its lower position heretofore described.

Oil entering the well from the sands rises in the shot hole and through the foot valve in the trap 10, filling the trap and eventually submerging and liquid sealing the minor flow or low pressure line 108 at the outside of the trap. When the line 108 is liquid sealed, pressure is built up in line 110 leading to the lower section of the bottom diaphragm chamber of the secondary valve mechanism greater than that supplied to the upper chamber through the line 112 due to submergence of the line 108, expanding the diaphragm and lifting the slide valve, thereby establishing communication between the branch 114 leading from the high pressure line and the line 115 leading to the upper section of the diaphragm chamber of the major valve motor, building up a pressure in said section of said diaphragm chamber which eventually, because of differential areas of the diaphragm in said chamber and the head of the major valve, shifts the valve and opens the major flow line to the top of the trap through the tubing 8; simultaneously opening the vent valve 123 in the fitting 117 that is connected with the major flow line; thereby relieving pressure on the bottom of the lower diaphragm of the

secondary valve mechanism so that the slide valve may be closed.

Air entering the trap or tubing above the oil displaces oil from the trap through the discharge line and Venturi tube. Oil leaving the trap through the tube in advance of the air moves through the tube at such low differential of velocity as to produce a negligible differential of pressure in the upper and lower sections of the upper diaphragm chamber of the secondary valve mechanism as to produce no operative effect on the diaphragm.

The discharging oil travels at increased velocity as the head rises in the line, thereby increasing the differential in the Venturi chamber and throat until, when the head of oil has been practically discharged, the differential in velocity has produced a differential of pressures in the respective sections of the upper diaphragm chamber of the secondary valve mechanism sufficient to permit the pressure in the upper section to expand the diaphragm, and thereby lower the stem 98 into thrust engagement with the slide valve to move the valve back to its original lowered position; thereby shutting off supply of air to the major valve motor and venting the upper section of the motor chamber so that the major valve may return to its seat under pressure of supply in the major flow line.

When the vent valve for the minor flow line is opened upon the initiation of major flow to the well, pressure beneath the lower diaphragm of the secondary valve mechanism is relieved to permit a quick return of the slide valve in response to the increase in differential of pressures in the upper diaphragm chamber so that operation of the secondary mechanism immediately follows the change in the differential in the upper chamber.

It is apparent from the foregoing disclosure that operation of the apparatus is entirely automatic in response to change of level of fluid in the well, and that the operation is responsive to differential pressures, and not affected by the difference in actual pressures encountered in wells of different depths and of conditions in different localities. Consequently, the apparatus is adaptable for universal use without necessity of adjustment for specific wells.

What I claim and desire to secure by Letters Patent is:

1. Pneumatic pumping apparatus including a well discharge line, a line, including a primary valve, for supplying air under pressure to the well for discharging liquid from the well through said discharge line, and secondary valve mechanism responsive to change in velocity of liquid in the discharge line controlling the valve in the supply line.

2. Pneumatic pumping apparatus including a well discharge line, a line, including a primary valve, for supplying air under pressure to the well for discharging liquid from

the well through said discharge line, and secondary valve mechanism responsive to differential velocities of liquid in the discharge line controlling the valve in the supply line.

5 3. Pneumatic pumping apparatus including, in combination with a well having a discharge line, a line for supplying air under pressure to the well for discharging fluid from the well through the discharge line, and

10 means responsive to change in pressures induced by change of level of liquid in the well for opening the supply line and to change in pressures induced by differential velocities of fluid in the discharge line for closing the

15 supply line.

4. Pneumatic pumping apparatus including a well discharge line having a Venturi tube, a line for conducting air under pressure to the well for discharging liquid through the discharge line, a valve for said line, a motor for said valve, a line for conducting air under pressure to said motor, a valve in said conducting line, means for controlling opening of the conducting line valve, a motor for closing the conducting line valve, and lines providing communication between the Venturi tube and said conducting line valve motor whereby said motor is operated in response to differential in pressures in the

30 Venturi tube.

5. Pneumatic pumping apparatus including a well discharge line having a Venturi throat, a line for supplying air to the well in major flow for discharge of liquid through the discharge line, a valve controlling the major flow line, a motor for said valve, a line for supplying air to said motor in minor flow for opening said valve, a secondary valve controlling the minor flow line, a diaphragm motor for the secondary valve, and lines leading from the discharge line and from the Venturi throat to opposite sides of said diaphragm, wherein change in pressures responsive to change of differential of velocities in the discharge line and Venturi throat are effective for actuating the secondary valve motor.

6. Pneumatic pumping apparatus including, in combination with a well, a trap in the well having a foot valve, a discharge line on the trap including a Venturi tube, a line for supplying a major flow of air to the trap for evacuating liquid contents thereof through the discharge line, a valve in the major flow line adapted for closure by pressure in the line, a motor for opening the valve, a line for conducting air to said motor in minor flow for opening said valve, a valve in said conducting line, a diaphragm motor for the conducting line valve, lines leading from the discharge line and Venturi throat to opposite sides of the motor diaphragm for closing the valve in the conducting line in response to increased differential of velocities of fluid in the Venturi tube, a di-

aphragm motor for opening the conducting line valve, lines for supplying air in minor flow to the well exterior to the trap and to the opening side of the motor for said conducting line, whereby the conducting line valve motors are adapted for balance by substantially equal pressures in the lines to the motor valves and the motors are operated respectively by change in pressures responsive to change of differential of velocities in the discharge line and to change in pressures responsive to liquid sealing of the minor flow line leading into the well.

In testimony whereof I affix my signature.
